United States Patent Office

Des. 203,897
Patented Feb. 22, 1966

203,897

CAN CARRIER OR SIMILAR ARTICLE

Paul Glenn Stephan, Landenburg, Pa., assignor to E. I.
du Pont de Nemours and Company, Wilmington, Del.,
a corporation of Delaware

Filed Aug. 28, 1964, Ser. No. 31,495

Term of patent 14 years

(Cl. D58—26)

FIG. 1

FIG. 2

FIG. 3

FIGURE 1 is a front elevation view of a can carrier or similar article, embodying my new design;

FIGURE 2 is a side view thereof; and,

FIGURE 3 is a bottom plan view thereof.

I claim:

The ornamental design for a can carrier or similar article, substantially as shown.
